UNITED STATES PATENT OFFICE.

SAMUEL N. LEOPOLD, OF CHICAGO, ILLINOIS, ASSIGNOR TO MORRIS PAPER MILLS, OF CHICAGO, ILLINOIS, A CORPORATION OF ILLINOIS.

COLLAPSIBLE CADDY.

Application filed October 27, 1921. Serial No. 510,859.

To all whom it may concern:

Be it known that I, SAMUEL N. LEOPOLD, a citizen of the United States, and a resident of Chicago, in the county of Cook and State 5 of Illinois, have invented certain new and useful Improvements in Collapsible Caddy, of which the following is a specification.

My invention relates to improvements in collapsible caddies, and is of particular 10 value in connection with caddies constructed of paper board or analogous material.

The patent to Henze, No. 1,198,032, is an example in the general class of paper receptacles to which my invention relates.

15 However, it will be observed that the receptacle of Henze is not collapsible and must therefore either be assembled and riveted or stapled together by the user or shipped to him in set up condition. The principal ob-

20 jects of my invention are to provide a receptacle of the class described and so constructed that it may be manufactured and shipped in collapsed or knocked down condition to the customer who is not required to perform

25 any mechanical operations on the same prior to the insertion of the goods therein; to provide a container of the class described which may be constructed from sheets of standard size with a minimum of waste; to provide

30 a construction which may be easily and quickly set up by relatively unskilled operatives; to provide a caddy of the class described which shall have an "all around" flange thereby making the receptacle sub-

35 stantially dirt and dust proof beside giving the same a finished and neat appearance; to provide a covered receptacle of the class described so constructed that the cover will maintain itself securely in position when

40 closed and will not tend to spring up out of closed position, and in general, to provide an improved and efficient construction of the character referred to.

In the drawings, which illustrate a preferred embodiment of the invention,

Fig. 1 is a side elevation partly in section of the improved caddy,

Fig. 2 is a plan view of the cover blank,

Fig. 3 is a plan view of the receptacle 50 with the cover open,

Fig. 4 is a section taken on the line 4—4 of Fig. 3,

Fig. 5 is a section taken on the line 5—5 of Fig. 3,

Fig. 6 is a section taken on the line 6—6 55 of Fig. 3,

Fig. 7 shows the caddy in flat condition ready for shipment to the consumer, and

Fig. 8 is a section on the line 8—8 of 60 Fig. 7.

Referring to the drawings, 10 represents as a whole the box or receptacle portion of the caddy, which portion is preferably constructed of a single sheet of paper board, the arrangement being such that said box portion may be collapsed or knocked down flat for shipping purposes, as is well known to those skilled in this particular art. Said box portion 10 includes front and rear walls 11 and 12 respectively, and side walls 13 and 14. All of said walls are equipped with internally extending flanges, as shown best at 15 in Fig. 3, which serve to strengthen the sides of the box while being of substantial value in preventing dirt or dust from entering the container.

The cover portion designated as a whole at 16 includes a lid part 17 which is flanged on all four sides. The side flanges 18 and 19 of the cover are simple integral extensions 80 of the lid part 17 bent up at right angles as shown in Fig. 4. The ends of the side flange parts 18 and 19 are formed with integral end extensions 20, 21, 22 and 23 which, when the cover is set up, co-operate with the end flange parts to maintain the flanges at right angles to the lid 17 and incidentally connect together the adjacent flanges.

The lid portion 17 of the cover is also equipped with integral end extensions 24 and 25 which form the outer portions of the front and rear cover flanges respectively. Said parts 24 and 25 themselves have extensions along their entire length, and in the case of the front flange portion 24, the terminal flap or extension 26 is continuous from end to end of the extension 24, that is to say, from side to side of the cover. The flap forming the extension of the rear flange member 25 of the cover is made in three parts 90 by slitting, as at 27 and 28, which slits provide a central portion or flap 29 and side flaps 30 and 31. The side flaps 30 and 31 serve the same purpose with respect to the rear of the cover as the flap 26 with respect to the front of the cover, while the intermediate flap portion 29 is secured to the top of a wall of the receptacle to serve as the fixed portion of

the hinge which connects the cover to the body.

In preparing the blanks for shipment to the consumer, the box portion is first of all united together by the usual staples or rivets 32 (see Fig. 1) after which the hinge flap 29 of the cover portion is united to the top of the rear wall 12 of the box portion by suitable staples as at 33. It will be noted that the outer surface of the blank for the cover is placed against the outer surface of the blank for the body or box portion. No other mechanical work or setting up of the box need be done by the manufacturer who is thus enabled to ship the box to the user in flat condition as indicated in Fig. 7. The setting up of the box by the user is accomplished as follows:

The blank is laid upon a table with the cover portion at the top, and the flange extensions 20, 21, 22 and 23 are bent at right angles to the flange members 18 and 19 so that they stand upright. The flange members 18 and 19 are then bent along their scored folding lines so as to extend at right angles to the lid portion 17. The front flange 24 is then bent up at right angles to the lid 17 so as to position it on the outside of, and in overlapping relation relative to, the side flange extension lugs 22 and 23. The flange extension 26 is then folded over on the inside of the front flange 24 so as to overlap and include between said parts 26 and 24 the flange lugs 22 and 23 which had previously been bent up into position. Said flap 26 is locked into this folded position by means of small ears 34 which are arranged to snap behind parts 35 partially separated from the main lid portion 17 by shearing as indicated at 36. After said parts 35 are sheared out they are pushed inwardly of the cover so as to present a substantial stop or abutment behind which the lugs 34 are locked in place. It will be understood that when folding over the flap portion 26 and locking same in position by lugs 34, said lugs 34, by reason of the resiliency of the material, are readily snapped behind the ears or abutment members 35.

The rear flange 25 is united to the side flanges 18 and 19 in substantially the same manner as is the front flange 24. However, on account of the fact that the portion 29 of the flap extension is utilized to form a part of the hinge for the cover, the flap members 30 and 31 are separate and not directly connected to each other, as in the case of the front flange flap 26. It will be manifest that the flaps 30 and 31 are folded over to include the parts 20 and 21 and are held in place by ears 37 with corresponding abutments 38 in the same manner as in the case of the front flange.

An important feature of my invention relates in the fact that by reason of the hinge

being constructed as an extension of the rear flange 25 which, when the cover is closed, is thus folded over through an angle of 180°, there is a substantial tendency for the resiliency of the material to force said parts away from each other, as indicated in Fig. 1. This tends to draw the cover as a whole backward and thus presses the inner surface of the front flange tightly against that portion of the front wall 11 of the receptacle part which it overlaps. Hence, the cover will very efficiently maintain itself in closed condition and will not become misplaced or gape open and allow dirt to enter.

Another important feature of my invention is the fact that by reason of the flange being extended all around the cover, the container is much more dirt proof than in the case of a receptacle such as shown in the Davidson Patent No. 1,372,218. In this connection it will be noted that the internal body flanges 15 extend under, and hence close the crevices in the cover due to the slitting of same to form the abutments 35.

Another advantage of my invention consists in the fact that the hinge is formed from a portion of the locking flap for the rear flange, and therefore no additional material is required.

In practice, I prefer to construct the body portion and the cover portion of the receptacle of the same kind and weight of material, namely, a good quality of multi-ply paper, one of the interior plies of which is coated or impregnated with a water proofing compound such as asphaltum. Such a paper stock is substantially waterproof and is highly effective in preventing deterioration of such goods as bakery products.

The described details of construction and manipulation are merely illustrative of a single phase of my invention, the scope of which should be determined by reference to the appended claims, said claims being construed as broadly as possible, consistent with the state of the art.

I claim as my invention:

1. In a container, the combination of a rectangular receptacle portion and a cover portion therefor comprising a lid having flanges integrally connected to the edges of the lid and adapted to overlap the four sides of the receptacle part when the cover is closed, one of said flanges having along its edge an intermediate and two end extension flaps, the intermediate extension flap being united to one of said sides and constituting with said flange a hinge for said cover, the end extension flaps constituting means for locking said flange to the adjacent flanges.

2. In a container, the combination of a rectangular receptacle portion and a cover portion therefor comprising a lid having flanges integrally connected to the edges of

the lid and adapted to overlap the four sides of the receptacle part when the cover is closed, one of said flanges having an intermediate and two end extension flaps, the intermediate extension flap being united to one of said sides and constituting with said flange a hinge for said cover, the end extension flaps constituting means for locking together said flange and the adjacent flanges, 5 said last named flanges having extension lugs adapted to be interfolded respectively between the said outer extensions and the other said flange.

3. A rectangular container cover provided along its edges with integral marginal flanges at right angles to the cover, two opposite flanges being formed with inwardly folded extensions and the other two flanges having flaps at their ends projecting un- 15 derneath said extensions to reinforce the corners, means integral with said extensions to secure them and the flaps in position, and a receptacle adapted to extend into the rectangle formed by said flanges, the middle 20 portion of one of the inwardly folded extensions being attached to one of the sides of the receptacle to act as a hinge.

4. A rectangular container cover provided along its edges with integral marginal flanges at right angles to the cover, two opposite flanges being formed with inwardly folded extensions and the other two flanges having flaps at their ends projecting un- 25

derneath said extensions to reinforce the corners, means integral with said extensions to secure them and the flaps in position, and a receptacle adapted to extend into the rectangle formed by said flanges, one of the inwardly folded extensions being slotted transversely near the securing means so as 40 to free the middle portion of said extension which is attached to one of the sides of the receptacle and acts as a hinge for the cover.

5. A rectangular container comprising a receptacle, a cover provided along its edges with integral flanges at right angles to the cover, two opposite flanges being formed with inwardly-folded extensions, the middle portion of one of the inwardly-folded extensions being attached to one of the sides of the container to act as a hinge and by its resilience in such folded condition serving to draw the other folded flange against the opposite side of the receptacle. 55

6. A container comprising a receptacle, a cover provided along its edges with flanges at right angles to the cover, one of said flanges having an inwardly folded extension secured to the outer surface of the receptacle, said flange and extension thereby serving as a hinge, the resilience of the fold between the flange and the extension serving to draw the opposite cover flange against the opposite side of the receptacle. 60

SAMUEL N. LEOPOLD.
